UNITED STATES PATENT OFFICE.

ROBERT J. SCHLOSSER AND HENRY R. FISHER, OF WARREN, PENNSYLVANIA, ASSIGNEES
TO THE PISO COMPANY, OF WARREN, PENNSYLVANIA, A CORPORATION OF PENNSYLVANIA.

BOTTLE-CORKING MACHINE.

No. 905,005.

Specification of Letters Patent. Patented Nov. 24, 1908.

Application filed July 23, 1907. Serial No. 385,104.

To all whom it may concern:

Be it known that we, ROBERT J. SCHLOSSER and HENRY R. FISHER, citizens of the United States, residing at Warren, in the county of 5 Warren and State of Pennsylvania, have invented new and useful Improvements in Bottle-Corking Machines, of which the following is a specification.

This invention relates to a machine for 10 corking bottles, and has for its object to provide a machine of such class, in a manner as hereinafter described, in which the complete operation of feeding the bottles and 15 inserting the cork, as well as feeding the cork to be inserted in the bottle necks will all be automatically and correlative effected.

Further objects of the invention are to 20 provide a machine of such class which shall be simple in its construction, strong, durable, efficient in its use, automatic in its operation, readily set up and inexpensive to manufacture.

With the foregoing and other objects in 25 view the invention consists in the novel construction, combination and arrangement of parts hereinafter more specifically described and illustrated in the accompanying drawings, wherein is shown the preferred 30 embodiment of the invention, but it is to be understood that changes, modifications and variations can be resorted to which come within the scope of the claims hereunto appended.

35 In describing the invention in detail reference is had to the accompanying drawings wherein like reference characters denote corresponding parts throughout the several views and in which—

40 Figure 1 is an elevation and longitudinal section of a machine for corking bottles in accordance with this invention; Fig. 2 is a sectional end elevation; Fig. 3 is a plan of the cork-carrying plate; Fig. 4 is a longitudinal sectional detail broken away illustrating the cork-feeding tubes, cork-carrying plate, compressor-carrying bar, cork compressor and further showing the manner of inserting a cork in the bottle neck, the cork 45 being shown in full lines in the compressor and in dotted lines in the bottle neck, and, Fig. 5 is a top plan broken away of the compressor-carrying bar and also showing a plurality of compressors.

Referring to the drawings by reference characters, 1 and 2 denote a pair of longitudinally-extending combined supporting and guide rails, each formed integral with, or connected to the end supports 3, 4 and the intermediate supports 5. The inner portion 6 of each of the rails 1, 2 constitutes a track upon which travels a bottle carrier 7. The bottles 8 are mounted upon the carrier in rows which extend transversely of the carrier 7. The carrier 7 is fed towards the means for inserting the corks (to be hereinafter described) in an intermittent manner to enable the said cork-inserting means to operate intermittently upon the rows of bottles so that during each corking operation a plurality of bottles will be corked. 70 To provide for the intermittent or step by step movement of the carrier 7 so that said carrier will be shifted in a longitudinal direction towards the cork-inserting means, 75 the carrier 7 has its lower face formed with a series of transversely-extending teeth 9, the teeth 9 being so disposed with respect to the rows of bottles that each tooth, when the bottles are positioned upon the carrier, will 80 be in vertical alinement with the necks of the bottles of a row. Adapted to intermittently engage the teeth 9 so as to cause the shifting of the carrier is a dog 10. The position of the dog 10 with respect to the teeth 85 of the carrier is that such dog is arranged to engage the teeth approximately centrally thereof. The dog 10 is pivoted, as at 11, to the upper end of a lever arm 12, the latter carrying a stud 13 which constitutes an abutment for the dog 10 when it is in engagement with a tooth 9 to shift the carrier, the stud 13 therefore arresting the swinging movement of the dog 10 in one direction. 90 The lower end of the lever arm 12 is pivotally connected as at 14 to a link 15 which has one end pivoted upon the cross rod 16 mounted in the intermediate supports 5. The other end of the link 15 is attached, as at 17 to an eccentric rod 18 carried by the 100 strap 20 of the eccentric 21 which is mounted upon the operating shaft 22. The latter is journaled in the intermediate supports 5 and has each end projecting therefrom. One of the projecting ends of the shaft 22 105 carries a pinion 23, the function of which will be hereinafter referred to and the other projecting end of said shaft 22 carries a

- drive pulley 24 operated from a prime mover (not shown), and which is adapted to be clutched to and unclutched from the shaft 22 in a manner as hereinafter set forth.
- 5 From the foregoing arrangement of parts it is evident that when the shaft 22 is rotated, motion will be imparted to the eccentric 21 which, through the medium of the rod 17, will actuate the link 15, and the latter in
- 10 turn will shift the lever arm 12, causing the dog 10 to engage a tooth 9 and shift the carrier 7 a distance necessary to position a row of bottles to receive corks driven in the necks of the bottles in a manner as herein-
- 15 after referred to.

Projecting upwardly from each of the combined guide and supporting bars is an upright 26 connected together at their tops by the transversely-extending cross member 20 27 which is formed at each end with an opening constituting guides for the reciprocating rods 28 for actuating the cork drivers 30 which are secured to a transversely-extending bar 31 attached to the rods 28.

25 These latter are actuated through eccentrics 28^a carried by the shaft 22. The bar 31 is attached to the rods 28 below the cross member 27. The function of the cork drivers 30 is to force the corks through the cork-carrying

30 plate, the cork compressors, and into the bottle necks.

Secured between the uprights 26 is a frame 32 having each side thereof provided with a longitudinally-extending ledge 33 constituting a track, as well as a support for the shiftable cork-carrying plate 34. The latter is formed with a centrally-disposed rectangular opening 35 in which is mounted a pair of cork transmitters each formed of two members, the members of one transmitter being indicated by the reference characters 36, 37, while the members of the other transmitter are indicated by the reference characters 38, 39. The members 36, 38 are stationary relative to the plate 34, while the members 37, 39 are adjustable. The members 36, 38 are formed with a series of semicylindrical grooves 40, while the members 37, 39 are formed with like grooves 41. The grooves 40 of the members 36, 38 oppose the grooves of the members 37, 39, thereby providing each of the transmitters with a series of circular openings to receive the corks when they are fed thereto from the cork supply means.

45 Normally, the member 37 is held in engagement with the member 36 and a like arrangement is had in connection with the member 38 with respect to the member 39 through the medium of a pair of compression springs 42 which are interposed between the members 37, 39. The springs 42 are carried by the bars 43 having screw-threaded ends, the said bars extending through the plate 34 and carrying on their

50 screw-threaded ends the nuts 44. The bars

43 also carry fixed collars 45 which abut against the members 35, 38 for permanently retaining them against the plate 34. The members 37, 39 are adapted to be shifted from the members 36, 38 so as to enlarge 70 the cork-receiving openings to facilitate the entrance of the corks and for this purpose stationary shifting arms are carried by the frame 32. These arms are indicated by the reference characters 46, 47 and are arranged 75 in pairs. The arms 46 are adapted to engage the member 37 for shifting it and the arms 47 are adapted to engage the member 38 for shifting it. The shifting of the member 37 is alternate with respect to the shifting of the member 39. To prevent the corks falling through the transmitters when they are opened a thin plate 34^a is arranged below said transmitters and secured to the frame 32, the plate 34^a having a centrally-arranged opening 34^b to allow of the operation of the cork drivers. The plate 34^a is not as wide as the frame 32 forming a clearance 34^c at each side. To provide for the operation of the arms 46, as well as the arms 47, the plate 34 is formed with a series of passages 48 shown in dotted lines in Fig. 3 and in full lines in Fig. 4. The plate 34 is adapted to be reciprocated and when reciprocated in one direction the arms 46 will 95 shift the member 37 and when the plate 34 is moved in the opposite direction the arms 47 will shift the member 39. This arrangement is had in view of the fact that the transmitters alternately receive the corks 100 from the cork supplying mechanism, and furthermore the transmitters are alternately positioned with respect to the compressors, the latter to be hereinafter referred to. The plate 34 is reciprocated through the medium 105 of a bell-crank lever having an extension 49 which is fixed at one end to a transversely-extending rock shaft 49^a. The bell crank has one arm 50 thereof pivoted as at 51 in the lugs 52 which depend from the lower 110 face of the plate 34 and extend through the clearance 34^c. The other arm 53 of the bell crank extends between a pair of rollers 54, 55, carried by a reciprocating slide bar 56 moving through the keepers 57 fixed to an 115 upright 26 and an intermediate support 5. Attached to the slide bar 56 by the pin 58 is a link 59 which is eccentrically connected as at 60 to a gear 61 which meshes with the pinion 23. The other end of the rock shaft 120 49^a carries a lever arm 49^b which is pivotally connected to the lugs 49^c which depend from the lower face of the plate 34 and extend through the clearance 34^c.

From the foregoing arrangement it is evident that when the shaft 22 is rotated, motion will be transferred from the pinion 23 to the gear 61, which actuating the link 59, will reciprocate the slide bar 56. On the upward movement of the bar 56 the roller 55 130

will engage the arm 53 of the bell crank, rocking the shaft 49^a, moving the arms 49^b, 50, thereby shifting the plate 34 in one direction and when the bar 56 lowers the roller 54 will engage the arm 53, actuate the arms 49^b and 50 and move the plate 34 in an opposite direction. The movement of the plate, however, owing to the arrangement of the rollers with respect to the arm 53 of the bell crank is such that when the plate is at the limit of its movement in one direction it will remain stationary a sufficient time so as to enable the operation of the drivers to force the corks from a transerrer, through 10 the compressors and into the bottle neck.

The reference character 62 denotes a cork compressor-carrying bar supported upon the vertical members 63, these latter being actuated by the cams 64 carried by the shaft 22. 20 The members 63 extend through and are guided by the combined guide and supporting rails 1, 2. The compressor carrying bar 62 extends transversely of the machine and is arranged in the path of the drivers 30 and 25 at each end thereof the bar 62 is formed with an opening 65 and through which extend rods 28. The bar 62 is formed with an elongated opening extending in the direction of the length thereof, as at 65, with the side 30 walls of said openings shouldered as at 66 and within the openings 65 is loosely mounted a plurality of cork guides 67. These compressors are shouldered, as at 68, such shoulders being adapted to seat upon the shoulders 35 66 of the bar 62. Each of the combined guides and compressors 67 is formed with a conoidal-shaped opening 69 the wall of which compresses the cork and is further provided on its lower face with a nip 70 for centering the 40 compressor with respect to the bottle neck, as clearly shown in Fig. 4. The mounting of the compressors in a loose manner in the bar 62 allows for the automatic adjustment thereof owing to the irregularities in the bottle neck, particularly in regard to the height 45 thereof. The automatic adjustment of a compressor is clearly shown in Fig. 4. The function of the compressors 67 is not only to compress the cork as it is being driven 50 into the bottle neck as clearly shown in Fig. 4, but also to strip the cork in view of the fact that the cork is not driven entirely in the bottle neck, the position of the cork when driven in the bottle neck being slightly above 55 the mouth of the bottle, with the projecting end extending into the compressor. This is clearly shown in Fig. 4. After the drivers have positioned the corks in the bottle necks in a manner as shown in Fig. 4 the bar 62 60 is elevated, carrying the compressors therewith and consequently the compressor will be stripped of the cork. The vertical movement of the bar 62 is had against the pull of the springs 71 so that as the members 63 lower the pull of the spring 71 will cause the

bar 62 to position the compressors 67 in operative relation with respect to the mouths of the bottles.

The means for feeding the corks to the transerrers consists of two series of cork tubes 72, the number of cork tubes of each series corresponding to the number of cork-receiving openings of a transerrer. The tubes of each series are braced at their tops by a clamping member 73. These members 75 are connected together by a cross piece 74. The tubes of each series at their bottoms are supported by a transversely-extending member 75, openings 76 being provided in the member 75 and into each extends the lower 80 ends of the cork tubes. Flanges 77 are provided on the lower end of each cork tube and which rest upon the members 75. The members 75 are so positioned with respect to the cork transerrers that the plate 34 will act 85 to cut off the supply of corks from one series of tubes, while the corks of the other series of tubes are being supplied to a transerrer.

The reference character 78 denotes a clutch mounted upon the shaft 22 and which is 90 adapted to be brought into engagement with the pulley 24, thereby clutching it to the shaft 22 so as to rotate the latter. After the last row of bottles has been corked the clutch 78 is automatically moved out of engagement 95 with the pulley 24, thereby discontinuing the operation of the shaft 22. The means for automatically moving the clutch 78 out of engagement with the pulley 24 to unclutch the latter from the shaft 22 consists of a 100 block 79 attached to one side of the carrier and which is adapted to engage and shift in a lateral direction, the lever arm 80 so as to elevate the vertically-extending member 81 having its upper end formed with a hook 82 105 and its lower end pivotally connected as at 83 to a hinged rod 86 carrying a roller 87 which bears against a bar 88 pivoted at its lower end as at 89 and attached intermediate its ends to the clutch 78. A guide 90 is 110 provided for the vertically-extending member 81. When the lever 80 is moved laterally by the block 79 the member 81 will be elevated carrying the arm 86 therewith in an upward direction. The movement of the 115 arm 86 in such manner will force the bar 88 outwardly which in turn will carry the clutch 78 free of the pulley 24, consequently unclutching the latter from the shaft 22. To retain the member 81 in its vertically-adjusted position, one of the rods 28 carries on its upper end a hook-shaped member 91 120 adapted to engage the hook-shaped end of the member 81 and consequently the latter will be retained in its vertically-adjusted position, thereby maintaining the shifted position of the rod 86 so as to prevent the clutch 78 from engaging with the pulley 24. By disconnecting the hooked end 82 from the hook member 91 the clutch 78 can be moved 125 130

to clutch the pulley 24 to the shaft 22, thereby throwing the machine into operation.

It is thought that the operation of the machine can be thoroughly understood from the detailed operation set forth in regard to the various mechanisms, but it will be stated that the shifting of the carrier to position a row of bottles to be corked is had when the drivers 30 start to return to their inoperative position. After the drivers are moved clear of the transferrers the plate 34 is moved in an opposite direction so as to position the transfer which has received a set of corks in the path of the drivers while the other transfer from which the corks have been ejected is positioned to receive another supply of corks. After the last row of bottles has been corked the clutch mechanism is thrown out of operation so as to discontinue the actuation of the various mechanisms of the machine. It will furthermore be stated that as the drivers return towards their inoperative position the cams 64 elevate the rods 71 so as to move the bar 62 vertically thereby causing the corks to be stripped from the compressors.

What we claim is—

1. A machine of the character described comprising a frame, a reciprocatory plate mounted upon said frame, a pair of cork-transferrers carried by said plate and adapted to receive the corks from an independent cork supply, and means carried by the frame and adapted to extend in the plate and engage the transferrers for adjusting them, thereby facilitating therein the entrance of the corks received from the supply.

2. A machine of the character described comprising a frame, a reciprocatory plate supported thereby, a pair of transferrers carried by the plate and adapted to alternately receive corks from an independent cork supply, and means fixed to the frame and adapted to extend in the plate during the reciprocations thereof, thereby adjusting the transferrers to facilitate the entrance therein of the corks received from the supply.

3. A machine for corking bottles comprising cork drivers, a carrier for shifting the bottles to a position to be corked, automatically-adjustable cork guides arranged in the path of the drivers, a plurality of separate cork supplies, a pair of cork-transferrers alternately receiving corks from one of said supplies, and means for alternately positioning said transferrers over the guides in the path of the drivers.

4. A machine of the character described comprising cork drivers, a bottle carrier for shifting the bottles to a position to be corked, means for intermittently shifting said carrier, automatically-adjustable cork guides arranged in the path of said drivers, a cork supply, a pair of cork transferrers, and a reciprocatory plate for alternately position-

ing the transferrers over the guides and in the path of the drivers.

5. A machine of the character described, comprising cork drivers, a bottle carrier for shifting the bottles to a position to be corked, means for intermittently shifting said carrier, automatically-adjustable cork guides arranged in the path of said drivers, a cork supply, a pair of cork transferrers, a reciprocatory plate for alternately positioning the transferrers over the guides and in the path of the drivers, means for reciprocating said drivers, and means for reciprocating said plate.

6. A machine of the character described comprising a bottle carrier, means for inserting corks in the necks of the bottles, an operating means therefor and for said carrier, a clutch mechanism for connecting said operating means with a prime mover, and a clutch shifting mechanism adapted to be actuated by a carrier for throwing the clutch mechanism to inoperative position, thereby discontinuing the operation of said operating means.

7. A machine for corking bottles comprising reciprocatory cork drivers, a pair of cork transferrers operating at right angles with respect to the direction of the cork drivers, a vertically-adjustable cork compressor bar, automatically-adjustable cork guides mounted in said bar, means for alternately positioning a transfer over said guides, and a carrier adapted to position the bottles beneath the guides and in the path of the drivers.

8. A machine for corking bottles comprising reciprocatory cork drivers, a pair of cork transferrers operating at right angles with respect to the direction of the cork drivers, a vertically-adjustable cork compressor bar, automatically-adjustable cork guides mounted in said bar, means for alternately positioning a transfer over said guides, a carrier adapted to position the bottles beneath the guides and in the path of the drivers, an operating shaft, means actuated from said operating shaft for reciprocating the drivers, means actuated from said operating shaft for shifting said compressor bar, means actuated from said shaft for shifting the cork transferrers, means actuated from said shaft for shifting the carrier, a clutch for connecting said shaft to a prime mover, and means actuated by the carrier for throwing said clutch to an inoperative position, thereby discontinuing the operation of the machine.

9. A machine for corking bottles comprising cork drivers, a carrier for intermittently shifting rows of bottles to a position to be corked, a pair of cork supplies, a pair of transferrers adapted to alternately receive corks from said supplies, means for opening one of the transferrers to facilitate the en-

90

95

100

110

115

120

125

130

trance of the corks received from said supplies, and a reciprocatory plate carrying said transmitters for positioning the corks in the path of said drivers.

5 10. A machine of the character described, comprising a pair of cork transmitters, each comprising a pair of grooved members, one of which is adjustable, the grooves of one member opposing the grooves of the other member forming thereby cork receiving 10 openings, means for shifting said adjustable member from the stationary member thereby increasing the size of the cork receiving openings to facilitate the entrance of the 15 corks therein, and means whereby said adjustable member is automatically returned to normal position, thereby decreasing the size of said openings.

11. A machine of the character described 20 comprising a pair of cork transmitters, each comprising a pair of grooved members one of which is adjustable, the grooves of one member opposing the grooves of the other member, forming thereby cork receiving 25 openings, means for shifting said adjustable member from the stationary member thereby increasing the size of the cork receiving openings to facilitate the entrance of the corks therein, means whereby said adjustable member is automatically returned to 30 normal position thereby decreasing the size

of said openings, cork drivers, and means whereby said transmitters position the corks in the path of said drivers.

12. A machine of the character described 35 comprising a pair of cork transmitters, each comprising a pair of grooved members one of which is adjustable, the grooves of one member opposing the grooves of the other member forming thereby cork receiving 40 openings, means for shifting said adjustable member from the stationary member, thereby increasing the size of the cork receiving 45 openings to facilitate the entrance of the corks therein, means whereby said adjustable member is automatically returned to normal position thereby decreasing the size of said openings, cork drivers, means whereby said transmitters position the corks in the path of said drivers, and a carrier for 50 intermittently positioning rows of bottles with the mouths of the bottles of each row in the path of said drivers to receive the corks.

In testimony whereof we have hereunto 55 set our hands in presence of two subscribing witnesses.

ROBERT J. SCHLOSSER.
